UNITED STATES PATENT OFFICE

134,906

DESIGN FOR A WALLET

Morris Ladenburger, New York, N. Y.

Application December 9, 1942, Serial No. 108,988

Term of patent 14 years

To all whom it may concern:

Be it known that I, Morris Ladenburger, a national of the German Reich, residing at New York, in the county and State of New York, have invented a new, original, and ornamental Design for Wallets, of which the following is a specification, reference being had to the accompanying drawing, forming part thereof.

The figure is a plan view of a wallet, showing my new design.

The back of the wallet, not shown, is substantially plain.

I claim:

The ornamental design for a wallet, as shown and described.

MORRIS LADENBURGER.
